UNITED STATES PATENT OFFICE.

EMILE SCHEEMACKER, OF WOONSOCKET, RHODE ISLAND, AND GEORGES RAIMOND, OF BELLINGHAM, MASSACHUSETTS.

AEROPLANE.

Application filed August 2, 1922. Serial No. 579,256.

To all whom it may concern:

Be it known that we, EMILE SCHEEMACKER and GEORGES RAIMOND, citizens of the United States, residing at Woonsocket, 5 county of Providence, and Bellingham, in the county of Norfolk, respectively, and States of Rhode Island and Massachusetts, respectively, have invented certain new and useful Improvements in Aeroplanes, of 10 which the following is a specification.

The present invention relates to means for assisting aviators to clear themselves from aeroplanes in case of accident and reach the ground in safety.

15 The object is to provide a simple apparatus of a practical character and one that is under the control of the aviator for ejecting him from the fuselage and permit him to jump without danger of entanglement.

20 The preferred embodiment of the invention is shown in the accompanying drawings, wherein:—

Figure 1 is a view in side elevation with the parts in normal or inoperative condition,

25 Figure 2 is a similar view, but showing the apparatus in its ejecting relation,

Figure 3 is a detail sectional view with the parts as shown in Figure 1,

30 Figure 4 is a detail sectional view with the ejecting means extended,

Figure 5 is a front elevation of the mechanism shown in Figure 4.

The aeroplane, which may be of any desired character, is shown as provided with a standard type of fuselage 6 and planes 7, the upper plane having a central recess 8 in its rear side, as indicated in Figure 2.

An upwardly movable seat 9 is located in 40 the fuselage and is pivotally mounted, as shown at 10, to the upper end of lazy tongs 11, said tongs being mounted by a pivot pin 12 at its lower end in the lower portion of the fuselage. Suitable cross springs 13, connecting opposite sections of the lazy tongs, serve to urge the same towards each other and thus extend the tongs in a well known manner. Ordinarily, however, these tongs are maintained in collapsed or folded condition, beneath the seat, as shown in Figure 3.

This holding means includes a pair of oppositely disposed latch levers 14 carried by the seat, and having pins 15 that engage in sockets 16 in the opposite side walls of the 55 fuselage. The levers terminate at their up-

per ends in suitable hand grips 17. Other holding means comprise oppositely disposed hooks 18 pivotally mounted in the lower portion of the fuselage, as shown at 19, said hooks being arranged to take over cross pins 60 20 on the lower end of the lazy tongs. The hooks 18 are connected by an equalizer bar 21, and this bar has a pivotal connection 22 with an actuating lever 23. The lever 23 is connected to a foot treadle 24 arranged in 65 advance of the operator's seat 9.

Said seat 9 has connected to its rear lower portion a coiled spring 25 which is also connected, as shown at 26, to the lazy tongs. This spring serves to turn the seat 9 rearwardly upon the lazy tongs when the latter are extended. A foot piece 27 is pivotally mounted on the lower front side of the seat so that it may be folded up against the same, and chains or other fasteners 28 serve to 70 75 limit its downward movement to a horizontal position.

The fuselage is provided directly in rear of the seat-retaining recess with a parachute pocket 29 having an upwardly moving bottom 30 carried by springs 31. A cover 32 for the pocket has a spring hinge 33 which serves to swing said cover upwardly. The cover, however, is normally held in closed position by a rearwardly extending flange 34 that overlies the same and is carried by the seat 9.

The operation of this apparatus is substantially as follows. Under normal conditions the seat 9 is held down in the fuselage by the hooks 18 and the latches 14—15. In case of an accident the aviator has only to release the latches 14—15 and press upon the treadle 24. The seat being thus released, the springs 13 will cause the elongation of the lazy tongs and eject the seat from the fuselage. At the same time the spring 25 will act to swing said seat so that as the aeroplane plunges downward the seat will be in approximately horizontal position 100 and the aviator standing upon the foot piece 27, as indicated in Figure 2, will be free from contact with the plane.

A parachute, as A, to which the aviator is strapped, is carried in the pocket 29 upon the plunger bottom 30 and is normally held therein by the cover 32 which in turn is held in closed position by the flange 34 of the seat. As said seat rises, obviously the cover 33 will be released and the plunger 105 110

- bottom 30 will expel the parachute. The aviator can thus leave the aeroplane with a relatively great degree of safety and descend by the parachute to the ground.
5. From the foregoing, it is thought that the construction, operation and many advantages of the herein described invention will be apparent to those skilled in the art, without further description, and it will be 10 understood that various changes in the size, shape, proportion and minor details of construction may be resorted to without departing from the spirit or sacrificing any of the advantages of the invention.
15. Having thus fully described our invention, what we claim as new, and desire to secure by Letters Patent, is:—
1. In an aeroplane, a fuselage, a seat member movably mounted therein, a lazy tongs 20 on which the seat is mounted, means for elongating the lazy tongs to eject the seat from the fuselage, and means for normally locking the seat against such ejection.
  2. In an aeroplane, a fuselage, a seat member movably mounted therein, a lazy tongs 25 on which the seat is mounted, springs engaged with the lazy tongs for ejecting the seat from the fuselage, and means for normally locking the seat against such ejection.
  3. In an aeroplane, a fuselage, a seat member movably mounted therein, a lazy tongs 30 on which the seat is mounted, means for elongating the lazy tongs to eject the seat from the fuselage, holding hooks engaging the lazy tongs to hold them in collapsed condition and means for operating the hooks to release the lazy tongs.
  4. In an aeroplane, a fuselage, a seat member movably mounted therein, a lazy tongs 35 on which the seat is mounted, means for elongating the lazy tongs to eject the seat from the fuselage, oppositely disposed pivoted holding hooks engaging the lazy tongs to hold them in collapsed condition, an equalizer bar connecting the tongs, and an actuating device connected to the equalizing bar.
  5. In an aeroplane, the combination with 40 a fuselage, of a seat removable therefrom, means for ejecting the seat, a connection between the seat and ejecting means that permits the former to tilt with respect to the ejecting means, and means for automatically causing the seat to tilt when ejected.
  6. In an aeroplane, the combination with 45 a fuselage, of a seat removable therefrom, means for ejecting the seat, a pivotal connection between the seat and the ejecting
- means that permits the former to tilt on the latter, and means for effecting said tilting movement.
7. In an aeroplane, the combination with a fuselage, of a seat removable therefrom, means for ejecting the seat, a pivotal connection between the seat and the ejecting means that permits the former to tilt on the latter, and a spring between the seat and ejecting means for swinging said seat.
8. In an aeroplane, the combination with 50 a fuselage, of a lazy tongs mounted therein, means for extending the lazy tongs, means for locking the lazy tongs against extension, a seat pivoted on the lazy tongs, and means for swinging the seat when the lazy 55 tongs are extended.
9. In an aeroplane, the combination with a fuselage, of a lazy tongs mounted therein, spring means for extending the lazy tongs, means for locking the lazy tongs against 60 extension, a seat pivoted on the lazy tongs, and a spring for swinging the seat when the lazy tongs are extended.
10. In an aeroplane, the combination with a fuselage, of a seat, means for ejecting the 65 seat from the fuselage, a parachute pocket in the fuselage in rear of the seat, a cover for the pocket, and means carried by the seat for holding the cover closed.
11. In an aeroplane, the combination with 70 a fuselage, of a seat, means for ejecting the seat from the fuselage, a parachute pocket in the fuselage in rear of the seat, a spring operated cover for the pocket, means carried by the seat and removable 75 therewith for holding the cover closed, and a spring-pressed ejector for the parachute located in the pocket.
12. In an aeroplane, the combination with 80 a fuselage, of a seat therein, a lazy tongs 85 supporting the seat, and to which it is pivoted, springs for elongating the lazy tongs, means for locking the lazy tongs against elongation, a spring for swinging the seat on the lazy tongs when the latter is extended, a parachute-holding pocket in the fuselage in rear of the seat, a spring-operated cover for the pocket, a holding device for the cover carried by the seat, and an ejector in the pocket operated when 90 the cover is opened.
